COMBINED SEAT, TABLE, AND WALKING UNIT FOR INFANTS

George B. Hansburg, Walker Valley, N.Y.

Application December 20, 1957, Serial No. 704,063

3 Claims. (Cl. 155—22)

This invention relates to the art of infants' furniture and more particularly to a combined seat, table and walking unit.

It is among the objects of the invention to provide a combined seat, table and walking unit which is neat, compact, relatively light in weight and though it may readily be collapsed for ease in transportation, is sturdy and long lasting and which, in addition to having utility during feeding of the infant, will provide a secure support for the infant seated therein, yet will permit the infant to walk in any desired direction while supporting a portion of its weight to take the strain off its legs.

According to the invention, the unit comprises a panel or table portion supported on legs above the floor. A seat is positioned in an opening in the center of the panel and is so suspended that it may readily be rotated in a complete circle and pivot to enable the infant's feet to reach the floor so that it may walk with a portion of its weight supported by the seat suspension.

In the accompanying drawings in which are shown one or more of various possible embodiments of the several features of the invention,

Fig. 1 is a side elevational view of the unit partly in cross section,

Fig. 2 is a fragmentary detail view on an enlarged scale, showing the seat suspension,

Fig. 2a is a perspective view of the leg rest,

Fig. 2b is a side elevational view of the leg rest,

Fig. 3 is a perspective view of the unit,

Fig. 4 is a sectional view taken along line 4—4 of Fig. 3, and

Fig. 5 is a perspective view of a leg mounting bracket.

Referring now to the drawings, the unit comprises a table surface, desirably a circular panel 10 of any suitable rigid material which may readily be cleaned to remove food particles, liquids and dirt, said panel 10 having a strip 11 of resilient material around its periphery to define a bumper.

The panel 10 is supported by four legs 12, each comprising a pair of telescoped tubes 13 and 14, each of the upper ends 15 of the outer tubes 14 being releasably secured in a bracket 16 affixed to the undersurface of panel 10 adjacent its periphery and designed to hold the legs 12 so that each extends outwardly at a slight angle from the vertical to provide added stability to the unit.

As shown in Figs. 4 and 5, each of the brackets 16 comprises a split sleeve portion 21 with diametrically opposed fingers 22, with openings 23 therein through which screws 24 may be inserted to secure the fingers 22 to the panel 10. Extending radially outward from sleeve portion 21 are parallel flanges 25, each with an outwardly extending lip 26 which have openings 27 through which screws 28 extend to secure said lips 26 to the panel.

The upper end 15 of the tube 14 is located in split sleeve portion 21 and secured therein by the tightening of bolt 31 which extends through flanges 25.

The tube 14 is provided with longitudinally spaced

2

openings 33 and as shown in Fig. 4, a stud 35 is adapted to extend through an opening 33' in tube 13 aligned with any one of said openings 33, said stud being urged outwardly by a spring 36 positioned in tube 13 so that the inner tube 13 may be adjusted to desired position with respect to outer tube 14 and releasably locked in position by stud 35 to adjust the height of the panel 10. The lower end of each of the tubes 13 has a caster 38 mounted thereon to facilitate movement of the unit.

The panel 10 is provided with a large opening 41 in its center, preferably circular as shown, to accommodate the infant, the periphery 42 of said opening 41 desirably having a strip 43 of resilient material affixed thereto to prevent injury to the infant, who will rest on a seat 45 accessible through said opening.

As shown in Figs. 1 and 3, the seat 45 desirably comprises a substantially rectangular plate of rigid material which may readily be cleaned and which is conformed at its forward edge 46 to accommodate the legs of an infant seated thereon.

The seat is supported so that it may readily be rotated in opening 41 and may readily tilt to facilitate use of the unit as a "walker."

To this end, as shown in Figs. 2 and 3, a plurality of L-shaped brackets 47 are provided, preferably equidistantly spaced around the periphery 42 of opening 41. The horizontal legs 48 of said brackets 47 are secured as by screws 49 to the undersurface of panel 10 inwardly of the periphery 42 and extending radially of said opening 41. Secured to the lower end of each of the vertical legs 51 of brackets 47 are flanged rollers 52, said rollers being arranged in a circle, as shown in Fig. 3.

Riding on said rollers 52 is a supporting ring 53 of rigid material such as steel which has its lower edge 54 straddled by the flanges on rollers 52 and its upper edge 55 spaced from the undersurface of panel 10 sufficiently to permit ready removal of the ring 53 for cleaning.

Secured to the ring 53 as by riveting and equidistantly spaced therearound, are four hooks 56, to each of which may releasably be secured the end 57 of a supporting strip 58 of resilient material such as a strong elastic tape.

Two of the diametrically opposed strips 58^a are secured as by riveting, to the side edges of plate 45 and the other diametrically opposed strips 58^b and 58^c are secured to the front and rear edges of the seat, respectively aligned with the center thereof.

The panel 10 on its upper surface is provided with a circular rail 61 supported on upstanding posts 62 and which slidably mount blocks 63 for the amusement of the infant.

In the use of the unit above described, the length of the legs 12 are adjusted so that when the infant is seated on the plate 45 with the latter in horizontal position, the four strips 58 will equally support the weight of the infant with its feet slightly spaced from the floor.

If the infant should want to walk, its normal action will be to attempt to stand which will require that the infant slide forward on the plate 45. As a result, the two central strips 58^a will act as a pivot for the plate 45 and as the major force will then be exerted against the front edge 46 of the plate 45, such front edge will move downwardly, the strip 58^b, which now supports substantially the entire weight of the infant, readily yielding. The infant will then be able to walk and since its weight is partially supported by the strips 58^a and 58^b, such walking action will be facilitated as the infant's legs will not have to support its entire weight.

If the infant wishes to change its direction of movement, this may be readily accomplished, for only the ring 53 mounted on rollers 52 will have to be rotated, and not the entire unit, and when the infant has turned so that it is facing in the desired direction, its forward ad-

advance is readily accomplished by reason of the casters on legs 12 of the unit.

When the infant is tired and wishes to be seated, as it lowers its body, it will also move backwardly. As a result, the rear strips 58^a will again take up the weight of the infant; as will the side strips 58^a and the front strip 58^b, and the strength of the four strips is sufficient to retain the infant in seated position with its feet spaced from the floor.

By reason of the front strip 58^b positioned between the legs of the infant, it cannot slide off the seat and there is no danger of injury.

To facilitate feeding of the infant, it is desirable to provide a leg rest 65 which will retain the feet of the infant away from the floor.

As shown in Figs. 2a and 2b, the leg rest 65 may include a leg support 66 comprising a pair of angle bars 67 which are pivotally mounted at one of their ends as at 68 to brackets 69 secured to seat 45 near its forward edge 46, a plate 71 of rigid material being secured to the angle bars 67 and extending transversely thereacross.

Pivotally connected to the other ends of the angle bars 67 as at 72 is a foot support 73 which desirably comprises a pair of angle bars 74 between which extends a plate 75 also of rigid material. As shown in Fig. 2b, the foot support 73 is designed to extend substantially at right angles from plate 71 and may be pivoted inwardly from such position to extend parallel to said plate 71.

In order to retain the leg rest 65 in operative position, a stop member 76 is secured to the undersurface of plate 71, said member 76 having a plurality of inclined slots 77 with which coacts the cross piece of a pivoted U-shaped detent 78.

The leg rest may readily be moved to inoperative position by pivoting the foot support 73 against plate 71 and then releasing the detent 78 from slots 77 so that the leg support 66 may be pivoted parallel to the undersurface of seat 45. When this is done, the detent 78 which had been previously aligned with the space between the pivots 68 and the adjacent edge of plate 71 is then pivoted also to extend parallel to seat 45 beneath the leg support 66. A latch 81 is pivotally mounted to the seat 45 releasably to retain the leg rest in inoperative position.

With the construction above described, a highly useful unit is provided which has utility as a feeding unit, an exercise unit and as a play-table and which may readily be cleaned so that it will remain in sanitary condition.

As many changes could be made in the above construction and many apparently widely different embodiments of this invention could be made without departing from the scope of the claims, it is intended that all matter

contained in the above description, or shown in the accompanying drawings, shall be interpreted as illustrative and not in a limiting sense.

Having thus described my invention, what I claim as new and desire to secure by Letters Patent of the United States is:

1. A table having a circular opening in the top surface thereof, said opening being of an area considerably less than the remaining area of the table, a plurality of legs supporting said table; each of said legs having a roller at the lower end thereof, a circular support, means mounting said support beneath said table for rotation thereof about an axis at right angles to said table, the periphery of said circular opening extending inwardly beyond the means mounting said support, a seat, a plurality of flexible elongated members each having one end secured to said seat and spaced therearound and their other end secured to said support normally to retain the seat in substantially horizontal position parallel to the plane of the table and normally aligned with said opening, and a leg rest mounted on said seat for movement to operative position to receive the feet of the user and to inoperative position beneath said seat and extending substantially parallel thereto and means releasably to lock said leg rest in both operative and inoperative positions.

2. The combination set forth in claim 1 in which said seat has front and rear edges and side edges, the elongated members are resilient and secured at one end to said seat to the front and rear edges thereof midway between the side edges and to the side edges thereof.

3. The combination set forth in claim 2 in which the outer periphery of said table and the periphery of said opening each has an annular resilient member secured thereto.
